HANDGRIP FOR SKI POLES

Earl A. Miller, Orem, Utah 84057

Filed Dec. 12, 1967, Ser. No. 9,750

Term of patent 14 years

(Cl. D34—14)

FIGURE 1 is a side elevational view as seen from the left of a handgrip for ski poles embodying my design,

FIGURE 2 is a top plan view of the handgrip,

FIGURE 3 is a plan view of such handgrip as viewed from below,

FIGURE 4 is a front elevational view of the handgrip embodying my design, and

FIGURE 5 is a side elevational view of such handgrip as viewed from the left.

I claim:

The ornamental design for a handgrip for ski poles, as shown.
